(57) **CLAIM**

I claim the ornamental design for a remote control caddy, as shown and described.

DESCRIPTION

FIG. 1 is a perspective view of a remote control caddy, showing my new design as draped over an arm of a couch; FIG. 2 is a front elevational view thereof, illustrated in a flat configuration;

FIG. 3 is a rear elevational view of FIG. 2; FIG. 4 is a right-side elevational view of FIG. 2, the left-side elevational view being a mirror image thereof;

FIG. 5 is a top plan view of FIG. 2; and,

FIG. 6 is a bottom plan view of FIG. 2.

The broken lines showing a couch and a remote control in a pocket in FIG. 1 depict environmental matter and form no part of the claimed design.
